UNITED STATES PATENT OFFICE.

ALBERT A. SMITH, OF RIVERDALE, AND ISAAC Q. GURNEE, OF BUTLER, NEW JERSEY.

DESIGN FOR A PIPE.

Application filed August 3, 1926. Serial No. 18,587. Term of patent 14 years.

To all whom it may concern:

Be it known that we, ALBERT A. SMITH and ISAAC Q. GURNEE, citizens of the United States, residing at Riverdale, in the county of Morris and State of New Jersey, and Butler, in the county of Morris and State of New Jersey, respectively, have invented a new, original, and ornamental Design for Pipes, of which the following is a specification, reference being had to the accompanying drawings, forming part thereof.

Figure 1 is a side view of the article showing our new design.

Fig. 2 is a top view; and
Figure 3 is an end view of same.
We claim:

The ornamental design for a pipe as shown.

Signed at Butler, in the county of Morris and State of New Jersey, this 6th day of July, 1926.

ALBERT A. SMITH.
ISAAC Q. GURNEE.
